(57) CLAIM

We claim the ornamental design for a cover for electronic device, as shown and described.

DESCRIPTION

FIG. 1 is the front perspective view of a cover for electronic device showing our new design;
FIG. 2 is the front view thereof;
FIG. 3 is the rear view thereof;
FIG. 4 is the left-side view thereof;
FIG. 5 is the right-side view thereof;
FIG. 6 is the top plan view thereof;
FIG. 7 is the bottom plan view thereof; and,
FIG. 8 is the front perspective view thereof shown in an example environment.

The broken lines in the drawing show unclaimed environment only and form no part of the claimed design.
